UNITED STATES PATENT OFFICE.

HUGH BONNER, OF NEW YORK, N. Y.

LIFE-SAVING NET FOR USE AT FIRES.

SPECIFICATION forming part of Letters Patent No. 360,082, dated March 29, 1887.

Application filed February 24, 1887. Serial No. 228,658. (No model.)

To all whom it may concern:

Be it known that I, HUGH BONNER, a citizen of the United States, residing at New York, in the county of New York and State of New York, have invented certain new and useful Improvements in Life-Saving Nets for Use at Fires, of which the following is a specification, reference being had therein to the accompanying drawing.

10 My invention relates to improvements in life-saving apparatus for use at fires; and the objects of my invention are to provide a net strong enough to resist the weight of bodies falling from a great height, and in which the 15 tension of the parts shall be equal, and which shall be provided with suitable means about its circumference for keeping the tension equal. I attain these objects by the mechanism illustrated in the accompanying drawing.

20 Heretofore nets or canvas used at fires for a similar purpose have consisted either of textile fabric with handles attached around the edge, or else of cotton webbing, in which the warp and woof were each in parallel lines and 25 sewed together at the points of crossing. These forms of apparatus were not sufficiently strong to resist the weight of falling bodies, and they were liable to sag. By means of my invention these difficulties are entirely removed.

30 In the drawing, A represents a central ring, preferably of steel, and preferably about eight inches in diameter, and preferably bronzed to prevent it from rusting. From this ring project radially the cords B to the outer ring, C, 35 which is composed of a stout rope, preferably of manila, and about one inch in thickness. Between the central ring, A, and the outer ring, C, are arranged in concentric circles rings

D, composed of strong rope, preferably of manila. The radial ropes B are knotted, spliced, 40 or seized to the central ring, A, and to each of the concentric rings D, and also to the outer ring, C, and these radial ropes B preferably extend entirely across the apparatus, crossing one another within the central ring, A. 45

All the parts of this apparatus should be of the strongest material, and the points of knotting, splicing, or seizing should be made perfectly secure.

In practice the outer ring, C, forms a continuous handle, which may be grasped by a large number of men, and as the radial lines B extend from the ring C directly toward the center, the outward pull upon the ring C will cause the entire apparatus to be perfectly taut, 55 and will cause the strain of any body falling upon it to be borne equally by all the parts. At the same time the construction of the apparatus is such that it may be rolled up and packed into a very small space. 60

I have found by experiment that the best size of apparatus is about ten feet in diameter.

What I claim as my invention, and desire to secure by Letters Patent, is—

A life-saving apparatus consisting of the 65 central ring, A, radial ropes B, outer ring, C, and intermediate concentric ropes, D, all securely knotted, spliced, or seized together, substantially as described.

In testimony whereof I affix my signature in 70 presence of two witnesses, this 19th day of February, 1887.

HUGH BONNER.
